UNITED STATES PATENT OFFICE.

HENRY PRICE BALL, OF NEW YORK, N. Y., ASSIGNOR TO THE GENERAL INCANDESCENT ARC LIGHT COMPANY, OF NEW YORK, A CORPORATION.

SYSTEM AND APPARATUS FOR OPERATING ELECTRIC SWITCHES.

No. 821,077.

Specification of Letters Patent.

Patented May 22, 1906.

Application filed September 30, 1902. Serial No. 125,436.

To all whom it may concern:

Be it known that I, HENRY PRICE BALL, a citizen of the United States, residing at New York, county of New York, State of New York, have invented certain new and useful Improvements in Systems and Apparatus for Operating Electric Switches, of which the following is a specification.

My invention relates to a system of operating electric switches from a distance, and, further, to the mechanism employed for effecting the required movement of the switches.

The object of my invention is to provide means whereby a switch or switches controlling an electrical distribution system or the different phases of the system will upon the occurrence of an overload act to open one or more of the conductors of the system.

A further object of my invention is a construction wherein a single motor device will serve to impart the required motion to any one or all of the switches, and, further, to provide for the manual, single, or simultaneous control of a switch or switches to produce definite results.

The accompanying diagram and drawings will serve to illustrate my invention, in which similar letters and numerals indicate like parts.

Figure 1 is a diagram illustrative of the circuit connections between the distribution system, the switch-actuating mechanism, and the current-producing device for energizing the switch-actuating mechanism. Fig. 2 is a section on the line X X of Fig. 3, showing an oil-switch and its actuating mechanism. Fig. 3 is a plan view showing three switches and the actuating mechanism therefor. Fig. 4 is a side elevation of one switch-actuating mechanism, taken on the line Y Y of Fig. 3. Fig. 5 is a front elevation of a single switch-actuating mechanism. Fig. 6 is a vertical section of a single switch-actuating mechanism, taken on the line Z Z of Fig. 4.

It will be understood that I may employ one or more switches in connection with a system of electrical distribution.

I will first describe the mechanical construction of the mechanism for operating the switch or switches and subsequently the electrical connection of such switch or switches with the distribution system and the source of energy for operating such switch or switches.

In the drawings, 10 indicates a switch-board. Supported on the back of the switch-board is an oil-well 11. Three of such oil-wells are indicated in Fig. 3. The switch mechanism of each oil-well consists of a pair of insulated contacts 12 and a reciprocating bridge-piece 13, which coacts with the contacts 12. The particular construction shown for the oil-well, contacts, and bridge-piece is in no sense essential and may be varied. I have, however, preferred to show a reciprocating bridge-piece, as it is the most convenient for illustration. Any form of switch mechanism may be employed in place of the oil-switch shown for making and breaking the circuit.

Secured to the front of the switchboard is an electromotor 14. The shaft 15 of the armature of the electromotor has secured to it at its upper end a worm 16, which engages with a worm-wheel 17, keyed to a shaft 18. Where a number of switches are employed, as shown in Fig. 3, but a single shaft, worm, and worm-wheel is required. The shaft 18 has its bearings in brackets 19, secured to the front of the switchboard. Located on the shaft 18 in front of each switch is a ratchet-wheel 20, provided with four teeth. This wheel is loose upon the shaft. Keyed upon the shaft 18 in front of the ratchet-wheel is a disk-wheel 21. The disk-wheel is provided with a pin 22, which projects horizontally toward the ratchet-wheel, and a similar pin 23 projects from the ratchet-wheel toward the disk-wheel. Surrounding the hub 24 of the disk-wheel 21 is a coiled spring 25, (best shown in Fig. 5,) the ends of which bear upon the pins 22 23. The object of introducing a spring between the ratchet-wheel 20 and the disk-wheel 21 is to form a cushion between such parts in order that when the disk-wheel is thrown into operation its movement will be gradually imparted to the ratchet-wheel, or, in other words, the starting-blow will be softened or cushioned. The ratchet-wheel 20 is adapted to be driven clockwise, as indicated by the arrow, Fig. 4.

Mounted on but not secured to the shaft 18 in front of each switch is an eccentric 26, Fig. 6, and pivoted on each eccentric is a double-arm latch 27, one arm of which, 28, is situated to the left and the other arm, 29, to the right of the eccentric, Figs. 5 and 6. The arm 29 is provided with a hook end 30. The

outer periphery of the eccentric 26 is grooved, as shown at 31, and situated in this groove is a strap 32, the ends of which are secured to a connecting-rod 33.

5 In order to maintain the strap 32 in close frictional contact with the eccentric 26, the spring-pressed rings 34 are employed. The rings 34 are loosely mounted on pins 34^a, secured to and projecting horizontally from the eccentric 26. Situated on the ends of the pins are the adjustable nuts 34^b, and between such nuts and the outer ring are helical springs 34^c. The rings 34 serve by reason of the friction which they exert to stop the rotation of the eccentric when the latch 27 is disengaged from the ratchet-wheel 20, as will be hereinafter explained. Instead of using the frictional disks 34 any other well-known means may be employed for holding the strap 20 32 in engagement with the eccentric 26.

Located behind the arm 29 of the latch 27 and mounted on a stud 35^a, projecting horizontally from the eccentric 26, is a spring 35, Fig. 4, which serves to exert pressure upon the latch 27 and to force it when released into engagement with the ratchet-wheel 20. The connecting-rod 33 is secured at its inner end to an arm 36, pivotally connected to the short arm of a bell-crank 37. To the long 30 arm of the bell-crank is pivotally connected a link 38, pivotally connected at its upper end to a rod 39, secured at its lower end to a bridge-piece 13.

It will be understood that as the connecting-rod 33 is reciprocated forward or backward the bridge-piece 13 will be brought into or out of contact with the contacts 12 in the oil-switch, thus making or breaking the contacts through the oil-switch.

40 Secured to the brackets 19 on each side of the shaft 18 and back of the ratchet-wheel 20, Fig. 4, of each switch are the horizontally-disposed solenoids 40 41, each provided with a movable core 42 43, and located behind each of the cores is a helical spring 44. These springs serve to normally press the cores forward and into the path of movement of the arm 28 of the latch 27.

It will be observed that owing to the fact 50 that the arms 28 29 of the latch 27 are connected they will have a coincident oscillating movement.

The mechanical operation of the switch-actuating mechanism so far as disclosed is as follows: The ratchet-wheel 20 is rotated clockwise by means of the motor 14, acting through the disk-wheel 21 and the interposed spring 25, and the arm 28 of the latch 27 is held, when the oil-switch is open—*i. e.*, when 60 in the position shown in Fig. 4—against the action of the spring 35 by means of the core 42 of the solenoid 40. If now this solenoid is excited by the passage of an electric current through it, the core 42 will be attracted 65 and the latch 27 under the action of the

spring 35 will be thrown forward into engagement, through its hook 30 on arm 29, with one of the teeth on the ratchet-wheel 20. The effect of this will be to rotate the ratchet-wheel 20 and the eccentric 26, which latter 70 will impart movement to the strap 32 and through it make traction upon the connecting-rod 33, its arm 36, bell-crank 37, which latter will actuate the link 38 and impart an upward movement to the rod 39 and bridge-piece 13 at its lower end to close the oil-switch. It will be observed that by the movement of the ratchet-wheel 20 the arm 28 of the latch 27 has been carried in front of the core 43 of the solenoid 41, and assuming 80 the solenoid 41 not to be excited such core will stop the forward movement of the arm 28 and release the hook 30 on the other arm 29 of the latch from engagement with the ratchet-wheel, thereby bringing the parts to 85 rest. Manifestly the movement of the parts to effect the opening of the oil-well will be the reverse of that described.

I will now describe how the cores 42 43 are actuated to control the movement of the 90 switch or switches.

Referring to Fig. 1, A A represent the conductors (three) of an alternating polyphase distributing system. Any number of conductors may be employed. B is a direct-current dynamo which serves to furnish the energy required to actuate the oil-switch-operating mechanism. C represents series transformers, one in each leg of the distributing system. D is an overload device, one in each 100 leg of the distributing system and each consisting of an actuating-solenoid E, having a core F, carrying a contact-making device G, adapted to coat with a pair of contacts H, connected to the terminals of the direct-current mains from the dynamo B. I represents hand-switches adapted through the instrumentality of springs J to normally occupy the position shown and which switches may be manually brought into contact with either of the contacts K or L, as desired, and for the purpose which will be explained. M is a switch which may be manually operated or automatically operated through the solenoid N to bridge the contacts O P.

The operation of my device to automatically or manually open an oil-switch is as follows: Assuming an oil switch or switches to be closed, the motor 14 at rest, the distributing system in operation, and the hand-switches I in the direct-current circuit in the position shown, should an overload occur in the distributing system—*i. e.*, in any leg or legs of such system—such overload will energize one of the series transformers C to a greater extent than normal, which in turn will energize one of the overload devices D. When the excitation of such overload device D occurs, it will attract its core F and close the direct-current circuit through contacts H and 110 I. This will open the contacts K and L, 115 and the motor 14 will start. The motor 14 will 120 rotate the disk-wheel 21 and the interposed spring 25, and the arm 28 of the latch 27 will be held, when the oil-switch is open—*i. e.*, when 125 in the position shown in Fig. 4—against the action of the spring 35 by means of the core 42 of the solenoid 40. If now this solenoid is excited by the passage of an electric current through it, the core 42 will be attracted 130 and the latch 27 under the action of the

solenoid N, which latter in turn will attract its core and cause the switch M to bridge the contacts O P, thereby throwing the current from the dynamo B onto the motor 14, which is set in operation. The movement of the motor 14 will rotate the shaft 18 and through it the disk-wheel 21 and ratchet-wheel 20. It will be observed that when the overload device acts to close the direct-current circuit 10 a current will be transmitted through one of the solenoids 41 and that such solenoid will attract its core 43, thereby permitting the latch 27 to have its arm 29 moved forward into engagement with the ratchet-wheel 20. 15 As soon as the latch engages with the ratchet-wheel the eccentric 26 is moved through one hundred and eighty degrees and the latch 27 correspondingly moved. At this point the arm 28 of the latch 27 is brought into contact 20 with an unattracted core 42 of a solenoid 40, which serves to release the latch, which brings the eccentric to rest—i. e., at rest in the position shown in Fig. 4—while the rotary movement of the ratchet-wheel 20 continues. The 25 movement of the eccentric through one hundred and eighty degrees, as described, produces a corresponding horizontal movement of the connecting-rod 33. In the condition of the switch as stated—i. e., with the oil-switch closed—the connecting-rod is moved to the right to bring the parts into the position shown in Fig. 2—i. e., with the circuit through the oil-switch broken. When it is 30 desired to close an oil-switch upon the cessation of an overload, the operator throws a 35 hand-switch I to cover a contact K. Should there be at such time an overload upon the line, both solenoids 40 41 will be excited and both cores 42 43 attracted; and the eccentric 40 will make one complete revolution and the connecting-rod one complete reciprocation, thereby moving the oil-switch parts from the open to the closed position and from the closed to the open position. If when the oil- 45 switch has reached its original position the overload still continues, the parts will continue to rotate, alternately making and breaking the circuit through the oil-switch until the overload has ceased. Obviously the motor may be stopped at any time by opening the switch M. Should it be desired to control the switch-actuating mechanism—for instance, to open the oil-switches independently of the overload devices, this may be accomplished by throwing a hand-switch I to cover a contact L. 55

I wish it understood that I do not limit myself to the employment of any particular type of transformer or overload device for closing the direct-current circuit upon the creation of an overload in any branch of the distributing-circuit, as many devices other than those shown may be used to accomplish the same result.

65 In the drawings I have shown the switches

I as independently located. Manifestly these switches may be connected and grouped at any one point, so as to be operated simultaneously or independently, as desired.

Having thus described my invention, I claim—

1. A system of controlling electric switches, comprising an alternating distributing system, a switch in each leg of said system, a motor device for moving said switches, means for automatically throwing said motor device into operative relation with said switches, and means for automatically controlling the movement of said switches individually.

2. A system of controlling electric switches, comprising an alternating distributing system, a switch in each leg of said system, a motor device for moving said switches, means for automatically throwing said motor device into operative relation with said switches, means for automatically controlling the movement of said switches individually, and means for manually controlling the movement of said switches.

3. A system of controlling electric switches, comprising an alternating distributing system, a switch in each leg of said system, a motor device for actuating said switches, an independent source of energy for actuating the motor device, and means energized by an increase in current in the distributing-circuit above the normal, which will close the circuit through the motor and selectively apply the movement imparted by the motor to the switches.

4. A system of controlling electric switches, comprising an alternating distributing system, a switch, a transformer and an overload device in each leg of the system, a motor device for moving the switches, an independent source of energy for moving the motor device, and means in the circuit of the motor device for selectively controlling the movement of the switches.

5. In a switch-actuating mechanism, the combination of a shaft, a motor for driving the shaft, an eccentric pivoted on the shaft, means for connecting and disconnecting the eccentric from the shaft, a switch mechanism, and means driven by the eccentric for actuating the switch mechanism.

6. In a switch-actuating mechanism, the combination of a shaft, a motor for driving the shaft, an eccentric pivoted on the shaft, means for connecting and disconnecting the eccentric from the shaft, means for controlling said connecting and disconnecting means, a switch mechanism, and means driven by the eccentric for actuating the switch mechanism.

7. In a switch-actuating mechanism, the combination of a shaft, a motor for driving the shaft, an eccentric pivoted upon the shaft, a ratchet driven by the shaft, means for connecting and disconnecting the eccentric and

ratchet, means for controlling said connecting and disconnecting means, a switch mechanism, and means driven by the eccentric for moving the switch mechanism.

5 8. In a switch-actuating mechanism, the combination of a shaft, a motor for driving the shaft, an eccentric pivoted on the shaft, a ratchet driven by the shaft, a spring-actuated latch device carried by the eccentric and adapted to coact with the ratchet, and a pair of solenoids having movable cores adapted to coöperate with the latch.

15 9. In a switch-actuating mechanism, the combination of a driven shaft, an eccentric pivoted on said shaft, a double-arm latch pivoted on said eccentric, a ratchet on the shaft, and means for controlling the engagement of the latch with the ratchet.

20 10. In a switch-actuating mechanism, the combination of a driven shaft, an eccentric pivoted on the shaft, a ratchet, means for throwing the eccentric into and out of engagement with the ratchet, a strap surrounding said eccentric, and means for holding said 25 strap in frictional engagement with said eccentric.

11. In a switch-actuating mechanism, the combination of a driven shaft, an eccentric pivoted on the shaft, a ratchet driven by the 30 shaft, a latch for connecting said eccentric to said ratchet, and electrical means for con-

trolling the engagement of said latch with said ratchet.

12. In a switch-actuating mechanism, the combination of a driven shaft, an eccentric 35 pivoted on the shaft, means for connecting said eccentric to the shaft, and electrical means for disconnecting said eccentric from said shaft.

13. In a switch-actuating mechanism, the combination of a driven shaft, a ratchet pivoted on the shaft, means for transmitting the power of the shaft elastically to the ratchet, an eccentric pivoted on the shaft, and means for transmitting the movement of the ratchet 45 to the eccentric when desired.

14. A system of controlling electric switches, comprising a motor, a source of energy therefor, a shaft driven by the motor, a series of switch-actuating mechanisms, a series of 50 switches adapted to be operated by the shaft, electrical means for controlling the switch-actuating mechanisms, said means having an automatically-acting part located at or near the switches, and a manually-controlled part 55 located at a distance from the switches.

In testimony whereof I affix my signature in the presence of two witnesses.
